UNITED STATES PATENT OFFICE.

WINTHROP L. TIDD, OF TAUNTON, MASSACHUSETTS.

COMBINED WRIST-STRAP AND COIN-HOLDER.

1,080,240.

Specification of Letters Patent.

Patented Dec. 2, 1913.

Application filed March 7, 1913. Serial No. 752,625.

To all whom it may concern:

Be it known that I, WINTHROP L. TIDD, a citizen of the United States, residing at Taunton, in the county of Bristol and State 5 of Massachusetts, have invented certain new and useful Improvements in Combined Wrist-Straps and Coin-Holders, of which the following is a specification.

My invention relates to certain novel improvements in a combined wrist-strap and coin-holder adapted to be worn by ladies, all as hereinafter set forth and claimed.

The object I have in view is to provide a more efficient coin holder combined with a 15 flexible strap capable of being detachably connected to the wrist; the holder proper being positioned in the strap so that, when in use, the wearer is enabled to manipulate the same with greater facility, as for example, when charging the device with the 20 coins or in removing them singly therefrom.

In the accompanying sheet of drawings, Figure 1 represents a top plan view of my improved combined wrist-strap and coin- 25 holder, the strap member lying flatwise; Fig. 2 is a similar view, the cover member of the coin-holder and portions of the strap being omitted; Fig. 3 is a partial longitudinal sectional view of the strap, taken on line 30 3—3 of Fig. 1; Fig. 4 is a partial vertical sectional view, in enlarged scale, taken through the coin-holder; and Fig. 5 represents a corresponding side elevation of it.

The following is a more detailed description of the device: The latter as a whole is 35 indicated by the letter A.

a indicates the flexible member or leather strap adapted to be removably attached to the wrist of the user; the center portion of 40 the strap is enlarged, as at a², and serves as a base for supporting the coin-holder C, later described. b indicates a similarly shaped central flexible member superimposed on the said part a² (Figs. 2 and 3) 45 and interlocking therewith through the medium of alining openings b¹, through which latter the respective end portions of the strap extend; as thus constructed a shallow space b⁴ is formed between the adjacent surfaces of the portions a² and b. The coin-holder C is formed of sheet metal and converted by suitable tools into the cylindrical hollow box-like article shown. The lower edge 50 of the vertical walls c is secured to the disk-like base c¹, the latter in turn being bent to produce a circular hollow beaded outer edge

c⁴; a portion of the latter is cut away at d¹ to form, in connection with the movable member h, a hinge-joint. The upper portion of the side c is inturned at right angles 60 to form a substantially semi-circular flat flange c⁵. See Figs. 2 and 4. The front or unflanged upper part of the wall is recessed circumferentially to form a passage t for coins or nickels, when the cover is swung upward. A movable cover member c² 65 surrounds the box-like holder C, its outer edge being turned or bent to produce a hollow circular rim c⁸, substantially like the said bottom edge c⁴. The rim c⁸ is made to snap over the top of the coin-holder to maintain the latter in the normally closed position; it is also cut away at d to receive the member h. This latter element h is comparatively thick and stiff and has oppositely disposed integral upper and lower journals or pintles h¹ movably mounted in the respective ends of the openings d¹, d of the hollow edges. See Fig. 5.

The interior of the container or holder is 80 constructed in a well-known way. That is, a light spiral spring s is surmounted by a follower f, the spring causing the follower to automatically press the coins n upward against the underside of said flanges c⁵.

In assembling the parts, the barrel c of the holder is snugly inserted in a circular hole b² therefor formed in the upper flexible member b; the edge of said hole has a notch b³ therein to receive the hinge bar h, 90 the latter being located diametrically opposite the outlet side of the container and in alinement therewith longitudinally of the strap. When thus mounted the lower rim c⁴ is held in the narrow vertical chamber or 95 space b⁴ separating the enlarged central portions b, a² of the flexible members. The rim c² of the cover is hinged to the upper end of the vertical bar h, the latter also being hinged to the lower rim c⁴. As thus constructed and mounted, the nickel-charged holder C of the device A, when worn on the user's wrist, is adapted to be easily and quickly manipulated, first swinging the cover rearwardly as indicated by dotted lines, 100 Fig. 2, at the same time the user presses slightly upon the upper exposed nickel n and slides it forward flatwise out of the holder, followed by a light tap upon the cover to return it to the normally closed position; the operation just described being 105 accomplished in two or three seconds. It

will be noted that the member *h* also serves to prevent the holder from becoming accidentally displaced.

I do not claim broadly a wrist-strap provided with means adapted for holding and dispensing coins therefrom; my invention relates more particularly to the construction of the strap, the manner of mounting the coin-holder therein and also the manner of 10 hinging the cover to the holder. As thus constructed and arranged, the device is practically solderless, and, when in use, is capable of being readily manipulated by the fingers of one hand.

15 I claim as my invention:—

1. A flexible wrist-strap having an enlarged integral portion intermediate its ends, a superimposed flexible member having a circular central hole therein, the said 20 last-named member having the other flexible member threaded in and extending longitudinally therethrough, the combination therewith of a coin-holder having an enlarged outer base interposed flatwise between the adjacent faces of said flexible members, the side walls of the body of the holder snugly fitting the circular hole formed in said superimposed member and extending upwardly therethrough, a cover, a 25

relatively thick bar extending upwardly 30 through and fitting a notch or recess formed in the said upper flexible member to secure the holder against axial bodily movement and having said bar member hinged both to said enlarged base and cover members, constructed and arranged whereby, when in use, the cover and the bar are adapted to be easily and quickly swung rearwardly on their hinges to permit the removal of a coin laterally from the holder.

2. The combination with a wrist-strap, of a coin-holder held and positioned therein, a hinged cover member, said coin-holder having the peripheral edges or rim portions of its base and cover extending circumferentially beyond the walls of its body or barrel part, and a vertically disposed movable hinge-bar jointed both to the said outer rims of the base and cover, said bar also engaging an opening or recess formed in the wrist-strap, whereby the coin-holder is held bodily 45 against axial movement.

50 In testimony whereof I have affixed my signature in presence of two witnesses.

WINTHROP L. TIDD.
